E. E. THIEL

PRINTING PLATE HOLDER

Filed August 22, 1924

INVENTOR:
EMIL E. THIEL

BY *Allen & Allen*
ATTORNEYS.

UNITED STATES PATENT OFFICE.

EMIL E. THIEL, OF CINCINNATI, OHIO, ASSIGNOR TO THE PRINTING MACHINERY COMPANY, OF CINCINNATI, OHIO, A CORPORATION OF OHIO.

PRINTING-PLATE HOLDER.

Application filed August 22, 1924. Serial No. 733,645.

To all whom it may concern:

Be it known that I, EMIL E. THIEL, a citizen of the United States, and a resident of Cincinnati, in the county of Hamilton and State of Ohio, have invented certain new and useful Improvements in Printing-Plate Holders, of which the following is a full, clear, and exact description, reference being had to the accompanying drawing, 10 forming part of this specification.

My invention relates to devices adapted for use with a bed, for retaining printing plates and the like thereon. It further relates more particularly to such devices 15 where used with printing plate beds having numerous holes therein, into which the devices of my invention are dropped.

"Drop-in hooks" as such devices are termed commercially, usually comprise a 20 jaw, and a holder, the latter being adapted for dropping into the holes or channels in a printing plate bed, and some kind of means resulting in the operator being able to adjust the position of the parts so as to bring 25 the jaw up against a printing plate thereby holding the plate down on the bed, and also holding it against displacement in the plane of the bed.

It is the object of my invention to provide 30 a structure wherein the carrier is fixed, and the jaw movable, and in which the jaw is given its movement by a double acting member which imparts very rapid action, and at the same time imparts a thrust to the 35 jaw, and which is of self-locking type. More particularly it is my object to employ a right and left hand screw which is in engagement with the jaw and the carrier in right and left hand threaded sockets, so 40 that a turning of the screw will give a double movement, with threads of a pitch in the screw which will not permit any jogging loose thereof, when under stress. It is further my object to provide for a simple sturdy 45 structure of jaw and carrier with small number of parts and easy assembly and operation.

I accomplish my objects by that certain 50 construction and arrangement of parts to be hereinafter more specifically pointed out and claimed.

In the drawing:

Figure 1 is a top plan view of one of the devices located in a press bed.

Figure 2 is a section through the press 55 bed showing the device in side elevation.

Figure 3 is a like view to Figure 2 showing the device in rear elevation.

Figure 4 is a section on the line 4-4 60 Figure 3.

Figure 5 is a perspective view of the carrier.

I have illustrated a press bed 1 having 65 holes 2 therein for reception of the printing plate holders of my invention. The holes are provided with an enlargement 3 around the lower ends thereof, to provide a shoulder for engagement with a hold-down tongue or projection on the carrier portion of the device. 70

The carrier is formed with base 4 and two upright sides 5, 5, with the base projecting from what may be termed the forward edges of the sides in a tongue 6. The proportions of the carrier are such that it may be tipped into the holes in the press bed, and then straightened up in such a way that the tongue will lie under the shoulder in the base of the bed hole, and the carrier, as will be noted, holds the jaw between the uprights 75 so that when the jaw is pressed against a plate, the carrier can not be tilted out reversely to the manner of its insertion. Thus the carrier will not become dislodged when the jaw is in operation, but at other times 80 can be tilted in and out of the holes, at will.

The uprights of the carrier are provided with holes 7 for a pivot pin 7^a, and holes 8 for a pivot pin 8^a.

The jaw is formed with the usual head 9, 90 and a stem 10, which fits snugly between the uprights of the carrier, and has a screw socket 11 therein, communicating with a hole 12 that opens into the top of the jaw. The socket is formed with a left hand 95 thread. The stem has also a leg 13 which is secured by the pivot pin 7^a in pivotal relation with the forward edges of the uprights.

Mounted on the other pivot pin 8^a, is 100 a bearing block 14, which has a screw socket therein as at 15, same being right hand threaded. A screw 16 having a left hand threaded portion for engagement in the stem, and a right hand portion for engagement in the bearing block, is set into said respective parts. 105

The entire device is thus formed of a

carrier piece, a jaw piece, two pivot pins and a right and left hand screw, which is a very simple structure and easy to put together.

5 In operation the device is dropped into a press bed hole and a tool inserted to engage the squared socket 17 in the upper end of the screw, the tool passing through the hole 12.

10 The jaw will then be thrust either forward or retracted dependent upon how the screw is turned, and will be moved very rapidly into or out of engagement with a printing plate to be held on the bed. The 15 direction of the thrust is such as to insure a tight engagement of the back of the carrier with the hole in the bed, when the jaw is in engagement with the plate.

Having thus described my invention, 20 what I claim as new and desire to secure by Letters Patent, is:—

1. In a device of the character described, the combination of a carrier, a bearing block mounted on the carrier, and a jaw, means 25 for pivotally mounting the jaw in the carrier and a screw intermediate the jaw and bearing block, said screw having right and left hand threads, and the bearing block and

jaw having right and left hand threaded sockets to engage said screw, said screw being so placed that turning thereof moves the jaw with relation to the carrier. 30

2. In a device of the character described, the combination with a carrier having a base, and interspaced sides, a bearing block, and a jaw, each being pivotally mounted in the carrier, a right and left hand screw available for turning through the jaw, and right and left hand sockets in the jaw and the bearing block for said screw, for the 35 purpose described. 40

3. In a device of the character described, the combination of a carrier having a base, and upright sides, a jaw having a threaded socket therein, opening through the top of 45 the jaw, a pivoted bearing block in the carrier, means for movably mounting the jaw in the carrier, and said bearing block having a threaded socket for an adjusting screw, said two threaded sockets being right and 50 left threaded respectively, and an adjusting screw having a right and a left hand threaded portion set into said two sockets, for the purpose described.

EMIL E. THIEL.
